(57) **CLAIM**

The ornamental design for a pet food container as shown and described.

DESCRIPTION

FIG. 1 is a perspective view of a first embodiment of a pet food container showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the pet food container shown in an open configuration;

FIG. 10 is a perspective view of a second embodiment of a pet food container showing my new design;

FIG. 11 is another perspective view thereof;

FIG. 12 is a front view thereof;

FIG. 13 is a rear view thereof;

FIG. 14 is a left side view thereof;

FIG. 15 is a right side view thereof;

FIG. 16 is a top plan thereof;

FIG. 17 is a bottom plan thereof; and,

FIG. 18 is a perspective view of the pet food container, shown in an open configuration.

The dash-dash broken lines in the drawings depict portions of the pet food container that form no part of the claimed design.
